THERMALLY INSULATED JUG OR THE LIKE

Stig O. A. Ek, Grona Gatan 4, Jonkoping, Sweden

Filed Oct. 25, 1961, Ser. No. 67,274

Term of patent 14 years

(Cl. D58—5)

FIG. 1

FIG. 2

FIGURE 1 is a perspective view of the thermally insulated jug or the like, showing my new design;

I claim:

The ornamental design for a thermally insulated jug or the like, as shown.
